Patented Apr. 6, 1920.

FIG. 2

FIG. 3

Inventor

J. W. Starr

By Watson E. Coleman

Attorney

UNITED STATES PATENT OFFICE.

JOHN W. STARR, OF CHARLESTON, WASHINGTON.

KEROSENE-BURNER FOR RANGES.

1,336,103.

Specification of Letters Patent.

Patented Apr. 6, 1920.

Application filed March 19, 1919. Serial No. 283,450.

To all whom it may concern:

Be it known that I, JOHN W. STARR, a citizen of the United States, residing at Charleston, in the county of Kitsap and

5 State of Washington, have invented certain new and useful Improvements in Kerosene-Burners for Ranges, of which the following is a specification, reference being had to the accompanying drawings.

10 This invention relates to oil burners, and particularly to burners for burning kerosene oil.

15 The general object of the invention is to provide a very simple form of kerosene burner which may be installed in ranges or like stoves or furnaces.

20 Another object of the invention is to provide means for heating the kerosene after introduction into the fire box of the stove whereby to gasify the kerosene.

25 A further object is to provide means for reheating the gas just prior to its introduction into the burner proper and still another object is to provide a stabilizing chamber into which the gasified kerosene shall be directed and from which gas shall pass through the discharge nipple, said stabilizing chamber insuring a steady and continuous flow of gas under minimum pressure.

30 Another object is to provide means to spread the gas flame issuing from the discharge nipple of the burner so that the flame may permeate and extend throughout the entire fire box of the range.

35 Still another object is to provide improved means whereby the pipe may be cleaned of soot or other foreign matter.

Other objects will appear in the course of the following description.

40 My invention is illustrated in the accompanying drawings, wherein:—

Figure 1 is a vertical sectional view of a range showing my improved kerosene burner applied thereto;

45 Fig. 2 is a longitudinal sectional view on the line 2—2 of Fig. 1, and

Fig. 3 is a fragmentary section of a blow-out valve.

Referring to these drawings, 10 designates the range itself with a fire box 11 of any suitable character. Disposed within the fire box is a stabilizing chamber 12, which terminates at its upper end in a burner nipple 13 having a central opening, the discharge through this burner nipple being reg-

ulated by a needle valve 14 extending down through the stabilizing chamber 12.

Entering the fire box is a pipe 15 by which kerosene is introduced to the burner. This pipe 15 is provided with a suitable valve 15^a 60 whereby the flow of kerosene may be regulated and the pipe is intended to be connected to any suitable reservoir. The pipe 15 enters the fire box and then extends upwardly therein and extends across and 65 approximately over the burner. Mounted upon the transversely extending portion 16 of the pipe 15 is a spreader 17 which is disposed directly above the burner nipple 13. This spreader serves to disseminate the 70 flame and also forms a protection to the pipe 16. It further acts to conduct heat to the pipe 16, thereby changing the liquid kerosene into a gaseous state. Of course the spreader 17 protects the pipe 16 against 75 direct contact with the flame.

The pipe 16 extends across the fire box, then downward, and transversely, but to one side of the burner nipple 13, then it extends again downward and transversely as 80 at 18. This transverse portion 18, while it is disposed slightly above the burner nipple 13, is to one side of this burner nipple, as illustrated in Fig. 2, and this portion 18 is connected by two pipes 19, to 85 the stabilizing chamber 12. At the extremity of the pipe 18, there is provided an outlet valve 20 controlled by means of a valve spindle 21 and when this outlet valve 20 is open, compressed air may be blown 90 through the pipe 15 which will blow out through the opening controlled by the valve 20 any soot or other foreign matter which may collect within the burner pipe.

It will be seen that with this construction 95 the liquid kerosene or like fuel is first transferred into a vapor in the portion 16 of the pipe which is heated by conduction through the spreader 17. This gasified or vaporized fuel is then conducted down to the portion 100 18 where it is again heated by the heat of the flame discharged from the nipple 13. The gas is then conducted into the stabilizing chamber 12 and discharged from the nipple 13. This stabilizing chamber I regard as of great importance, as it insures 105 a steady and continuous flow of gas, even under minimum pressure.

It will be seen that my burner is very simple, that it can use kerosene or other hy- 110

dro-carbons of like character, that the fuel will be placed in the very best condition possible for combustion, and that the pipes may be readily cleaned of soot or other foreign matter.

I claim:—

In an oil burner of the character described, a stabilizing chamber having a discharge nozzle, a valve carried by and extending through the chamber into the nozzle for controlling the discharge of vapor from the nozzle, means conveying vaporized oil

through the stabilizing chamber and for supporting said chamber including a pipe disposed in close proximity to the flame issuing from the nozzle, and pipes carried by the first named pipe and connecting the chamber to the first mentioned pipe. 15

In testimony whereof I hereunto affix my signature in the presence of two witnesses. 20

JOHN W. STARR.
